US00D836626S

(12) **United States Design Patent** (10) Patent No.: **US D836,626 S**
(45) Date of Patent: **** Dec. 25, 2018**

(54) **INTERACTIVE AUDIOVISUAL DEVICE**

(71) Applicant: **BEIJING RESEARCH & DEVELOPMENT CENTER of CHINA AVIC AVIONICS SYSTEMS CO., LTD.**, Beijing (CN)

(72) Inventor: **Qun Gu**, Beijing (CN)

(73) Assignee: **BEIJING RESEARCH & DEVELOPMENT CENTER OF CHINA AVIC AVIONICS SYSTEMS CO., LTD.**, Beijing (CN)

(**) Term: **15 Years**

(21) Appl. No.: **29/616,833**

(22) Filed: **Sep. 8, 2017**

(30) **Foreign Application Priority Data**

Mar. 9, 2017 (CN) 2017 3 0066327

(51) LOC (11) Cl. **14-02**

(52) U.S. Cl.

USPC **D14/314**

(58) **Field of Classification Search**

(57) **CLAIM**

The ornamental design for an interactive audiovisual device, as shown and described.

DESCRIPTION

FIG. 1 is a front elevational view of a interactive audiovisual device showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left perspective view thereof;

FIG. 8 is a front, right perspective view thereof; and,

FIG. 9 is a top, front, right perspective view thereof.

1 Claim, 9 Drawing Sheets
